UNITED STATES PATENT OFFICE.

JOSEPH BARRETT, OF NEW YORK, N. Y., ASSIGNOR TO NEW BRUNSWICK CARPET COMPANY, OF NEW BRUNSWICK, NEW JERSEY.

DESIGN FOR A CARPET-PATTERN.

Specification forming part of Design No. 6,012, dated July 30, 1872.

Specification describing a new and original Design for a Carpet, invented by JOSEPH BARRETT, of the city, county, and State of New York.

The accompanying photograph fully illustrates my invention.

This invention relates to a new carpet-design in which there are two main figures and a scroll background of peculiar outline. The larger of the two main figures has rounded projections at the ends, and embraces an oval with projecting straight sides. Within the

oval is a four-lobed figure, having small rosettes in the angles. The other main figure is oblong, rounded off concave at the corners, and ornamented internally, in manner shown. The groundwork is of scroll-work, and decorated with peculiar leaves of beautiful outline.

I claim as my invention—

The design for a carpet, as shown.
JOSEPH BARRETT.
